UNITED STATES PATENT OFFICE.

CORNELL FLAGSTAD, OF MINNEAPOLIS, MINNESOTA, ASSIGNOR OF NINETY-FIVE ONE-HUNDREDTHS TO THE FOLDING CRATE & BOX COMPANY, OF MINNEAPOLIS, MINNESOTA, A CORPORATION OF MINNESOTA.

COLLAPSIBLE CRATE.

Application filed June 12, 1926. Serial No. 115,638.

This invention relates to collapsible crates or shipping carriers, and the primary object is to provide a comparatively simple and practical, yet highly efficient type of shipping crate, especially constructed and adapted for use in transporting wet batteries, and which may, when emptied of its contents, be quickly collapsed, or "knocked down", into a compact form for return shipment to the original consignor or shipper. Further and more specific objects will be disclosed in the course of the following specification, reference being had to the accompanying drawings, in which:

15 Fig. 1 is a perspective view of a set up crate showing a preferred embodiment of my invention.

Fig. 2 is a top or plan view of the crate as shown in Fig. 1, but with the cover in its 20 open position and with one end section folded in.

Fig. 3 is a plan view of the crate, shown in Fig. 1, when in its folded or collapsed condition.

25 Fig. 4 is a sectional view as on the irregular line 4—4 in Fig. 3.

Fig. 5 is a plan view of a modified form of the crate.

Fig. 6 is an enlarged detail view of the 30 cover locking device used in the crate.

Fig. 7 is an enlarged sectional detail view showing the method of locking the crate when collapsed, as in Fig. 4.

Fig. 8 is a detail section showing the same 35 locking device and how utilized to lock the cover when the crate is set up.

Figs. 9, 10, and 11 are enlarged perspective detail views of the end section locking devices employed in the crate structure 40 shown in Fig. 5.

Fig. 12 is a perspective end view of a 45 crate similar to the one shown in Fig. 1, but shows a further modification in the end latches.

Referring to the drawings more particularly and by reference characters, A designates the bottom or base section of a crate having side sections B and C, end sections D and E, and a cover or top section F. In 50 the modification shown in Fig. 5, the corresponding crate sections are designated by

the respective characters, A¹, B¹, C¹, D¹, E¹, and F¹, and in the crate indicated in Fig. 12 the corresponding parts are referred to as 55 A², B², C², D², E² and F².

The side, base, and cover sections of the 60 crate are preferably made up of crossed slats nailed together, while the end sections (see Figs. 1, 2, 3, 4, and 12), are preferably made up of single slats 13, having cross 65 cleats 14, and are hinged as at 15 to the ends of the base, so as to fold down flat upon the base when the crate is collapsed. The end sections D, E, D² and E² are preferably narrower than the width of the crate, for 70 the purpose of conserving material, but the crate shown in Fig. 5, being of a modified construction, requires that the end sections D¹ and E¹ be wide enough to fill between the side sections and interlock at their upper 75 outer corners, with the side sections, by the lock or corner latch devices shown in Figs. 9, 10, and 11.

Referring more specifically to the 80 crate shown in Figs. 1, 2, 3 and 4, it may be noted that the side sections B and C are hinged to the edges of the base A by respective sets of hinges 16 and 17, and that the cover F 85 hinges, as at 18, to the side section B and closes toward the opposite section C where it is secured by the latch G. The side sections B and C are provided with integral 90 end extensions 19, which serve as handles by which the crate may be carried, and also serve to support hinges 20 of end cross bars 95 21, which connect the side sections A and B. These cross bars cause the side sections to maintain parallel planes at all times, with respect to each other, and also serve as stops for the end sections which swing upwardly 100 against them. The hinges 16 are what I conveniently term as spanning hinges, and are so constructed that when the crate is collapsed, as in Fig. 4, the side section B will be parallel with but spaced from the base A 105 so as to provide room for the end sections between the base and the side section B. All of the hinges 18 and 20 each consists of two strap iron butts connected by a pintel, and although the pintels of the hinges 18 and 20 on the B side of the crate are in alignment, it will be noted that as the bars

100

21 are above the edges of the side sections and the cover F is below or between the upper ends of the side sections it is necessary to reverse the butts on the cover in 5 order to effect a proper closing of the crate as shown in Fig. 4.

When the end sections are considerably narrower than the width of the crate, as above mentioned, they cannot engage the 10 side sections A or B to brace the crate in its rectangular or set up position, as is the case in Fig. 5. To provide the proper bracing, therefore, I have recessed the bars 21, as at 22, so that they will receive the end sections, when the latter are swung up, and when in this position it will be obvious that the crate cannot be distorted from its set up position as the bars provide a rigid bracing connection between the side and end sections. 15 20 It may also be noted that the upper cleats 14 of the end sections, may serve as convenient supports for the ends of the cover section. In the modification shown in Fig. 12, instead of recessing the bar 21 to receive the end 25 section D², I provide the end section D² with an angle-iron bracket 23, the projecting flange of which has a notch to receive a detent or flange of an angle iron 24 secured upon the under side of the bar 21. With 30 the two members 23 and 24 locked together, as when the end section D² is held in its vertical position, it is obvious that the crate will be braced in substantially the same manner as in Fig. 1. After the cover F² has been 35 opened the end section may be folded down to release the latch 23—24.

It will be noted from Figs. 1, 2, 3, and 12 that the end sections D and E are provided with vertical extension H which extend substantially above the tops of the crates proper. The object of these extensions is two-fold, i. e., to serve as a warning to the 40 45 crate handlers that the crate should never be tipped or so loaded that the members H will be in any but an upright position; and, to prevent the crates from being piled parallel one on top of another thus increasing the danger of having a column of loaded crates tip over. The extensions will not, of course, prevent the crates from being stacked with the crates of each tier transversely of the crates below it, as there is no great danger of a series of crates so stacked to tip over. These precautions are considered as 50 55 of primary importance in crates designed for shipping liquid containers such as batteries, for in such instances the tipping or tumbling of the crate may result in harmful as well as expensive results.

When the crate is collapsed a finger 25, on the cover F, engages a strap 26 on the side section C, and thus prevents the folded crate from buckling up in the middle. The cover is secured, both when the crate is set up and 60 65 when collapsed, by the latch G comprising

sliding bolts 27 the extended or retracted positions of which are determined by spring held finger pieces 28. The construction of the members 27 and 28 is substantially identical with the latch shown in Figs. 5 and 6 70 75 80 85 90 of a co-pending application, Ser. No. 12,974, filed May 3, 1925, jointly by Oscar A. Flagstad and myself, for collapsible crate, and will therefore not here be described in detail or claimed. The method of employing the latch in the present instance, however, is of considerable importance, and may be described as follows: Secured upon the inner face of the side section C and at the upper edge thereof, are a pair of substantially J shaped members or catches 29, one for each latch G. (See Figs. 1, 2, 3, 4, 7, and 8). These hook shaped members 29 are so arranged that the bolts 27 may engage under them, either when the crate is set up, as in Figs. 1 and 8, or when the crate is collapsed, as in Figs. 4 and 7. In Fig. 5 the U-shaped loops 30 perform the same function in substantially the same way.

The modified crate shown in Fig. 5 is similar in many respects to the crates above described, the following differences, however, being noted in particular. As the end sections D¹ and E¹ of this crate are as long as the width between the side sections, the cross bars (like 21) are eliminated, and the end sections interlock, at their upper corners, directly with the side sections, to brace the crate and to limit the outward swinging movements of the side and end sections to the vertical or upright positions with respect to the base when the crate is set up for loading. The corner irons, for effecting this interlocking action are shown particularly in Figs. 9, 10 and 11, and each consists of a 95 100 105 110 115 120 125 socket member 31, attached to the side section, and a tongue or latch 32, attached to the end section. The angularly formed socket member is provided with a substantially F shaped slot or socket 33, which receives the head 34 of the tongue 32. Between the head and body of the member 32 is a reduced neck portion 35, which when it engages in the narrow portion of the slot 33, prevents the end sections from swinging out beyond the ends of the side sections, and it is obvious that the head 34 also locks the side sections to the ends. As the members 32 are nailed to the outer faces of the end sections it will be seen that the heads 34 are pulled into place and therefore any inward pressure against the end sections will not have a tendency to loosen the members 32 or the nails which secure them to the end sections.

It may here be noted that the crate structures here shown are common in many respects to the constructions shown in my co-pending application for collapsible crate, Serial No. 54,792, filed September 5th, 1925, 130

and to that extent the present application is a continuation of said application Ser. No. 54,792.

It is understood that suitable modifications may be made in the general design and structural details of the invention as herein shown and described, provided, however, that said modifications come within the spirit and scope of the appended claim.

Having now therefore fully shown and described my invention, what I claim to be new and desire to protect by Letters Patent is:

A collapsible crate comprising a base, hav-

ing side and end sections hinged thereto, and a cover hinged to one of the side sections, a 15 latch member carried by the other side section to receive a latch bolt carried by the cover, the construction of said latch member and bolt being such that they may be interlocked both when the crate is set up and 20 when collapsed, and a catch carried by the cover near its hinged edge for interlocking engagement with an adjacent crate portion when the crate is collapsed.

In testimony whereof I affix my signature.
CORNELL FLAGSTAD.
